UNITED STATES PATENT OFFICE

2,070,560

LIQUID DISPENSING APPARATUS

Eric H. Bradley, Dayton, Ohio, assignor to
 National Pumps Corporation, Dayton, Ohio, a
 corporation of Ohio

Application July 23, 1931, Serial No. 552,573

7 Claims. (Cl. 221—95)

This invention relates to liquid dispensing apparatus and more particularly to that type of gasoline dispensing apparatus commonly known as a meter pump and in which the liquid is discharged from a motor operated pump through a meter to a flexible delivery conduit or hose which conveys it to the point of discharge, usually the gasoline tank of an automobile. In such a pump the delivery conduit is usually provided at its discharge end with a nozzle having an automatically closing but manually opened valve for controlling the discharge of the liquid. Because of the fire hazard which results from the accidental discharge of gasoline it is desirable that the discharge of the gasoline from such a pump should be immediately interrupted when the delivery is completed. It has been proposed heretofore to provide for the automatic interruption of the discharge by so connecting the discharge controlling device with the hose that when the hose is pulled from its normal position to filling position the discharge controlling device will initiate the delivery of liquid and when the pull on the hose is relieved, so that it can be returned to its normal position, the discharge controlling device will interrupt the discharge. However, the manner of effecting the control as used in these prior devices was such that it did not fully meet the requirements and the apparatus was unsatisfactory.

One object of the invention is to provide a dispensing apparatus in which the discharge of liquid will be controlled by the movement of the hose, or delivery conduit, which will be simple in its construction, highly efficient in operation and will fully meet the requirements of such an apparatus.

A further object of the invention is to provide such an apparatus in which the actuating device, which controls the discharge of the liquid, will be operated to initiate such discharge when the hose is moved either outwardly or laterally with relation to the apparatus as a whole.

A further object of the invention is to provide such an apparatus in which the hose will be automatically returned to its normal position and the discharge of liquid interrupted should the hose be dropped or laid down by the operator without effort on his part to return it to its normal position.

A further object of the invention is to provide such an apparatus in which the connection between the actuating device which controls the discharge of the liquid and the hose will be such that this connection will not be interfered with or

adversely affected by the torsional twisting of the hose.

A further object of the invention is to provide such an apparatus in which the connection between the hose and the actuating device will be broken if subjected to abnormal strain, as when the hose is torn from the pump.

A further object of the invention is to provide such an apparatus in which the discharge of the liquid will be instantly interrupted when the pull on the hose is relieved.

Other objects of the invention will appear as the apparatus is described in detail.

In the accompanying drawing Fig. 1 is a side elevation of a discharge controlling mechanism for a meter pump, embodying my invention; Fig. 2 is a transverse section taken on the line 2—2 of Fig. 1; and Fig. 3 is a front elevation of the connection between the actuating device and the hose.

In the drawing I have illustrated one embodiment of my invention and have shown the same as applied to a meter pump, the main features of construction and operation of which are well known. As is customary in such pumps the mechanism is mounted within and upon a hollow standard or housing, a portion of which is shown at 5. Mounted within this housing is a pump 6 driven by a motor 7a, the pump and motor being shown conventionally. The pump is connected with a discharge pipe 7, interposed in which is the usual meter 8. Connected with the discharge pipe is a delivery conduit which is capable of swinging movement to permit it to be extended to the point of delivery, and in the particular type of pump here shown the upper end of the discharge pipe extends outwardly beyond the housing and the delivery conduit is in the form of a flexible hose 9, the inner end portion of which is connected with the discharge pipe and suspended therefrom in such a manner that it will extend in a generally downward direction and usually it will hang in an upright and substantially vertical position when not in use. The outer or discharge end of the delivery conduit has connected therewith a nozzle 10 in which is mounted a valve 11, not here shown in detail, but which is usually of the spring seated type, and which has a valve stem 12 extending into the path of an operating handle or lever 13 pivotally mounted on the nozzle and arranged within a guard 14. Both the guard and the handle 13 are slotted to receive a supporting member or hook 15 which is mounted on a suitable part of the pump and projects outwardly beyond the housing 5. In the present in-

stance, the supporting hook is rigidly secured to a supporting device 16 which is clamped about the discharge pipe 7. The supporting member has in its outer end an opening through which the hasp 5 of a padlock 17 may be inserted to retain the nozzle thereon, when the pump is to be locked up overnight, and this padlock also serves to prevent the handle 13 from being manipulated to open the valve 11. The delivery of liquid from the pump 10 being controlled by the valve in the nozzle it is necessary that the hose should remain full of liquid if the next customer is to receive full measure and in order to prevent the hose from being drained, between delivery operations, when the 15 pump is idle, I have interposed in the nozzle, between the valve 11 and the hose an outwardly opening check valve 18 which is held to its seat by a spring 19 of such strength that the valve will not open under the weight or gravity pressure of 20 the liquid in the hose but will open under pump pressure.

In the present embodiment of the invention the discharge of the liquid is controlled by controlling the operation of the pump by the motor 25 and this is effected by starting and stopping the motor. It will be obvious, however, that the control of the discharging of liquid may be effected in various ways. The motor 7 which operates the pump is an electric motor and is controlled by a 30 switch in the usual manner. The switch forms no part of the present invention and it is not here illustrated, the switch casing only being shown, at 20. An operating member, such as a rod 21, extends into the casing and is connected with 35 the switch and this rod is also operatively connected with an actuating device, here shown as a lever 22 pivotally mounted at 23, in the present instance on the supporting member 16. In the form here shown, the lower end of this lever is 40 turned downwardly and is provided with a slot 22a and the upper end of the operating rod 21 is bent substantially at right angles to the length of the rod and inserted in the slot, as shown at 24, thus establishing a lost motion connection be- 45 tween the lever and the rod. The upper end of the lever 22 is operatively connected with the hose and, in the arrangement here illustrated, it extends through a slot 25 in the housing and is connected with one end of a flexible member or 50 cable 26 which extends downwardly therefrom about a suitable guide 27 and has its other end connected with the hose 9 at a point spaced from the inner end of that hose, the arrangement being such that when a pull is exerted on the hose the 55 upright portion thereof swings transversely to its length and that pull will be exerted through the flexible member 26 to the actuating lever 22 and will close the motor switch, thereby setting the motor and pump in operation and initiating the 60 discharge of liquid from the pump to the hose. The connection between the hose and the lever is such that the movement of the hose in any direction in which it may be moved when extended to delivery position, that is either outwardly 65 or laterally, will cause the lever to be operated. To facilitate the operation when the hose is moved laterally I prefer that the guide 27 shall be swiveled and that guide is here shown as a sheave rotatably mounted in a sheave block 28 which 70 is pivotally mounted on a bracket 29 for movement about a vertical axis. Consequently the guide will automatically position itself according to the direction of pull on the hose. When a hose of this kind is stretched a torsional twist is 75 imparted thereto and by the use of a flexible con-

nexion between the hose and the lever I prevent any ill effects from this twisting of the hose and the apparatus will operate with freedom even though a substantial twist may have been imparted to the hose. Preferably the flexible member is 5 so connected with the hose that it may be adjusted lengthwise thereof to accommodate the point of connection to the length of the flexible member or to compensate for a stretch of hose. In the present instance, the end of the flexible member 10 is connected with a collar 30 which is clamped about the hose.

When the pull on the hose is relieved the actuating lever is automatically returned to its normal position, in which position the switch is open, 15 and is retained in that position until a pull is again exerted on the hose. In the present construction, this is accomplished by means of a spring 31 connected with the lever 22 and with a fixed part of the structure and so arranged that 20 it will exert a constant retractile force upon the lever and whenever this force exceeds the resistance offered by the hose to the movement of the lever the latter will be returned to its normal position. The lost motion connection between 25 the switch operating rod 21 and the lever permits the latter to have a greater movement than it is necessary to impart to the switch but due to this lost motion connection the switch will not be closed by the spring 31 until the last portion 30 of the movement of the lever. In order that the switch may be closed instantly when the pull on the hose is relieved I have provided a second spring 32 which acts directly upon the switch operating rod 21 and will cause that rod to move 35 with the lever during the initial return movement of the latter. As here shown, a cross bar 33 is rigidly secured to the actuating rod and one end of this bar is connected with the spring 32, in the present instance by a bolt 34 and nuts 35 which permit the tension of the spring 32 to be regulated. To prevent the force of the spring from being exerted on the switch members with possible resultant injury I have connected to the other end of the cross bar 33 a stop 36 which is 40 so arranged that when the switch has been moved to its fully open position the stop will engage the switch casing and prevent the further movement of the operating rod 21. As here illustrated, the stop 36 is secured to the cross bar 33 by a pin 37 45 which may be inserted in any one of a series of holes 38 in the stop so that the effective position thereof may be varied.

I also prefer to interpose a spring between the flexible member 26 and the lever 22, as shown at 50 39, to protect the hose and other parts of the mechanism against excessive strain. The lever 22 is arranged above the nozzle support 15 and when fully extended contacts with that support. A violent pull on the hose might cause injury to 55 some part of the apparatus if the movement of the hose was positively stopped by the contact of the lever with the support, but the spring permits of a limited further movement of the hose and gradually checks that movement, thus not 60 only protecting the mechanism but also permitting the hose to be extended a greater distance than would otherwise be possible. The spring further serves to keep the slack out of the flexible member and prevents that member from 65 kinking.

It sometimes happens that the delivery hose will become entangled with the automobile in such a manner that when the automobile is driven away the hose will be torn from the pump 75

and in such an event it is necessary that the discharge of liquid be instantly stopped to avoid waste of gasoline and a serious fire hazard. I have therefore interposed between the flexible member 26 and the actuating lever 22 a yieldable device which serves to connect the flexible member with the lever and which will yield under abnormal strain to interrupt that connection and release the lever from the flexible member and from the hose, thereby permitting the switch to be opened. The yieldable connection is here shown as a hook 40 of ductile material, such as brass, which is hooked through the eye on the end of the spring 39. This hook is of sufficient strength to maintain the connection under all normal conditions but will yield under abnormal strain. I have also shown the other end of the flexible member connected with the clamp 38 on the hose by a similar hook 41 and it will be understood that the yieldable connection may be employed at either or both points as may seem desirable.

It will also be noted that the arrangement of the actuating lever is such that when the nozzle is mounted on the supporting hook 15 the guard 14 will extend into the path of the adjacent end of the lever and will prevent the latter from being moved far enough to close the switch, thereby preventing the mechanism from being tampered with and the motor started by unauthorized persons.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. In a dispensing apparatus comprising a discharge pipe, a delivery conduit connected with said discharge pipe and having its inner end portion suspended for swinging movement transverse to its length, and power operated means for discharging liquid through said pipe and said conduit, mechanism to control the discharge of liquid by said means including an actuating device movable to one position to initiate said discharge and to another position to interrupt said discharge, means for retaining said device normally in the position to interrupt the discharge, and a flexible member connecting said device with said conduit and so arranged that the transverse movement of said conduit in any one of a plurality of directions will cause said device to initiate said discharge, the connection between said flexible member and one of said parts being constructed to yield under abnormal strain and disconnect said flexible member from said part.

2. In a liquid dispensing apparatus, a delivery conduit having its inner end portion supported for swinging movement transverse to its length, a pump to discharge liquid through said conduit, and a motor to operate said pump, mechanism to control the operation of said pump by said motor and including an actuating device and means for holding said device normally in a position to prevent the operation of said pump by said motor, a swiveled guide supported below said actuating device, and a flexible member connected at one end with said device, extending about said guide and connected at its other end with said conduit at a point spaced from the inner end of said conduit.

3. In a liquid dispensing apparatus, a delivery conduit having its inner end portion supported for swinging movement transverse to its length, a pump to discharge liquid through said conduit, and a motor to operate said pump, mechanism to control the operation of said pump by said motor and including an actuating device and means for holding said device normally in a position to prevent the operation of said pump by said motor, a swiveled guide supported below said actuating device, a flexible member connected at one end with said device, extending about said guide and connected at its other end with said conduit at a point spaced from the inner end of said conduit, and a spring interposed between said flexible member and one of the parts with which it is connected.

4. In a liquid dispensing apparatus comprising a delivery conduit having its inner end portion supported for swinging movement transverse to its length, a pump to discharge liquid through said conduit, and a motor to operate said pump, mechanism to control the operation of said pump by said motor and including an actuating device and means for holding said device normally in a position to prevent the operation of said pump by said motor, and a flexible member connecting said device with said conduit and so arranged that the transverse movement of said conduit in any one of a plurality of directions will cause said device to initiate the operation of said pump by said motor, the connection between said flexible member and one of the parts with which it is connected including a yieldable device adapted to yield under abnormal strain and disconnect said conduit from said actuating device.

5. In a liquid dispensing apparatus comprising a delivery conduit having its inner end supported for swinging movement transverse to its length, a pump to deliver liquid to said conduit, an electric motor to operate said pump, and a switch for said motor, a lever, means for operatively connecting said lever with said switch, means tending to move said lever to a position to open said switch, a swiveled guide arranged below said lever, and a flexible member connected at one end with said lever, extending about said guide and connected at its other end with said conduit at a point spaced from the inner end of said conduit.

6. In a liquid dispensing apparatus comprising a delivery conduit having its inner end supported for swinging movement transverse to its length, a pump to deliver liquid to said conduit, an electric motor to operate said pump, and a switch for said motor, an operating member for said switch, a lever, a lost motion connection between said lever and said operating member, a spring acting on said lever to cause the same to impart movement to said operating member in a direction to open said switch, and a flexible member connecting said lever with said conduit at a point spaced from the inner end of the conduit.

7. In a dispensing apparatus comprising a delivery conduit having its inner end supported for swinging movement transverse to its length and having at its outer end a nozzle provided with a valve, an actuating handle for said valve and a guard for said handle, said guard and said handle having aligned slots, a pump to deliver liquid to said conduit, an electric motor to operate said pump, and a switch for said motor, a lever, means for operatively connecting said lever with said switch, a spring acting on said lever to move the same in a direction to open said switch, a flexible member connecting said lever with said conduit

and so arranged that the transverse movement of said conduit will move said lever in a direction to close said switch, a supporting member mounted adjacent to said lever, and adapted to extend through the slots in the guard and handle of said nozzle, and locking means to retain said guard

and said handle on said supporting member, said guard being then so arranged with relation to said lever that the latter cannot be moved to close said switch.

ERIC H. BRADLEY. 5
